Primary Examiner — T. Chase Nelson(74) *Attorney, Agent, or Firm* — Andrew F. Young, Esq.; Lackenbach Siegel, LLP(57) **CLAIM**

The ornamental design for a shoe sole, as shown and described.

DESCRIPTION

FIG. 1 is a rear perspective view of the present invention, shown in a right-foot orientation, a left-foot orientation being a mirror image thereof.

FIG. 2 is a right side elevation view of the embodiment shown in FIG. 1.

FIG. 3 is a left side elevation view of the embodiment shown in FIG. 1.

FIG. 4 is a rear elevation view of the embodiment shown in FIG. 1; and,

FIG. 5 is a bottom plan view of the embodiment shown in FIG. 1.

FIGS. 1-5 depict a first embodiment of a shoe sole for a right-foot orientation, a second embodiment is a shoe sole for a left-foot orientation, which is a mirror image thereof.

No claim is made to the upper construction, heel portions, or sole portions as shown by the use of dashed lines. The upper construction is shown as an environmental illustration only to aid the public. No claim is made to the dashed line regions on the shoe sole as the dashed lines indicate disclaimed portions forming no part of the claimed design.
